UNITED STATES PATENT OFFICE.

HENRY J. HARRISON, OF JUNEAU, ALASKA TERRITORY.

LAMP-HANGER.

SPECIFICATION forming part of Letters Patent No. 695,308, dated March 11, 1902.

Application filed September 5, 1901. Serial No. 74,404. (No model.)

To all whom it may concern:

Be it known that I, HENRY J. HARRISON, a citizen of the United States, and a resident of Juneau, in the Territory of Alaska, have 5 invented a new and Improved Lamp-Hanger, of which the following is a full, clear, and exact description.

This invention relates to a hanger for electric lamps; and the object is to provide means 10 similar to the usual shade-roller for carrying the flexible conducting-cord or wires, so that the lamp may be raised or lowered to any desired position without interfering in any way with the proper transmission of the electric 15 current.

This specification is a specific description of one form of the invention, while the claim is a definition of the actual scope thereof.

Reference is to be had to the accompanying 20 drawings, forming a part of this specification, in which similar characters of reference indicate corresponding parts in both views.

Figure 1 is a sectional elevation of the invention; and Fig. 2 is a detail view, with 25 parts in section, on the line 2 2 of Fig. 1.

a indicates a suitable framing on which is revolubly mounted through the medium of hollow journals *b* a drum *b*.

c indicates a spring, and *d* *d'* gears for actuating the drum *b* from the spring *c*.

e indicates any suitable mechanism similar, for example, to that usually employed in a spring shade-roller for holding the drum *b* in the desired position and yet for permitting 35 the drum to be adjusted from this position to another when desired. These devices *e* will be fully understood by reference to Fig. 2.

f indicates the lamp, and *g* the flexible conductors leading the current thereto. These 40 conductors are connected by fixtures *g'* with wires *h'*, leading into the drum *b*, and in turn connected with conducting-pins *h*, fastened in the drum *b* coincident with the axis thereof and extending through the hollow journals 45 *b'*. The pins *h* are insulated from the journals *b'* by means of non-conducting bushings, as shown in Fig. 1. The pins *h* project beyond

the journals of the drum *b* and beyond the frame *a* and have recessed ends receiving short projections *i* on spring-arms *i*. These 50 arms are mounted on the frame *a*, but insulated therefrom, and are in connection, respectively, with the poles of the electric circuit feeding the lamp *f*.

Now it will be clear that no matter in what 55 position the drum *b* be placed there will always be a proper electrical connection between the parts *h* and *i*, and the lamp will therefore be properly supplied with the electric current.

Various changes in the form, proportions, and minor details of my invention may be resorted to without departing from the spirit and scope of my invention. Hence I consider myself entitled to all such variations as may 65 lie within the scope of my claim.

Having thus described my invention, I claim as new and desire to secure by Letters Patent—

A lamp-hanger, comprising a frame having 70 depending parts, a shaft extending between said parts and mounted to turn therein, a spring driving the shaft, a drum, hollow trunnions on the drum, said trunnions being mounted in the depending parts of the frame, 75 gearing connecting the drum with the shaft, pins projected through the hollow trunnions of the drum and insulated therefrom, said pins extending into the drum and beyond said depending parts of the frame, contact- 80 arms fastened to the upper part of the frame and projecting downward and engaged respectively with said pins of the drum, electrical conductors adapted to be wound on the drum, said conductors being respectively in 85 connection with the pins, and means for controlling the movement of the drum.

In testimony whereof I have signed my name to this specification in the presence of two subscribing witnesses.

HENRY J. HARRISON.
